C. Harris & Paul W. Joiner, of Cincinnati, Ohio.
Letters Patent No. 1158 Dated Oct. 25. 1859.

The schedule referred to in these Letters Patent and making part of the same.

To all whom it may concern:

Be it Known that We, Conrad Harris and Paul W. Joiner, both of Cincinnati, County of Hamilton, State of Ohio, have invented or produced a new and original design for Wood Parlor Stoves, and we do hereby declare that the following is a full and exact description of the same, reference being had to the annexed drawings and to the letters of reference marked thereon, to wit:

Letter A, showing a perspective view of the stove.

Having thus fully set forth our joint invention, What we claim thereon as new and desire to secure by letters patent, is the scroll, flutings and mouldings as set forth in the accompanying drawings as forming an ornamental design for Wood Parlor Stoves.
